(57) CLAIM

The ornamental design for a bottle, as shown and described.

DESCRIPTION

FIG. 1 is a top, front, and left side perspective of the bottle; FIG. 2 is a top, rear, and left side perspective thereof; FIG. 3 is a front elevational view thereof; FIG. 4 is a right side elevational view thereof; FIG. 5 is a rear elevational view thereof; and, FIG. 6 is a sectional view of the bottle taken along line 6—6 of FIG. 4.

The dash-dash-dash lines shown in the drawings show the boundary of the claimed design.

The dash-dot-dash lines shown in the drawings are for environmental purposes only and form no part of the claimed design.
